1 Claim

ABSTRACT OF THE DISCLOSURE

An ignition point heat absorber for use on the ignition system of a combustion engine consisting of a conductive member mounted on the framework of a point breaker and having extended fins through which heat from said breaker will dissipate.

Summary of the invention

An ignition point heat absorber having a conductor mounted on the framework, said conductor terminating in a series of fins, and having a passageway therethrough to receive the fixed point of the ignition point assembly.

Brief description of the drawings

FIGURE 1 is a front elevational view of the device, showing the ignition point assembly in dotted lines.

FIGURE 2 is an exploded view of the device, and means for mounting same on the ignition assembly.

Description of the preferred embodiment

In the drawings the numeral 1 designates an ignition breaker point assembly having the fixed point 2 and the movable point 3. An L-bar 4, formed of a heat conductive material such as aluminum, has the orifice 5 therein through which the fixed point 2 extends and a back bar 6, made of the same material as that of the L-bar 4, is provided for ready mounting of the L-bar in position.

The upwardly extended end of the L-bar 4 is divided into a series of fins 7, 7 and the base member of the L-bar has the passageways 8, 8 which are in alignment with the passageways 9, 9 in the backbar 6. Bolts 10, 10 extend through the passageways 8, 9 and are maintained in position by the nuts 11, 11. One end of the back bar 6 is upwardly turned, as at 12, to offset the framework 1.

The L-bar 4 is placed on the frame 1 with the fixed point 2 extending through the passageway 3, and the back

2

bar 6 is placed under the framework 1 with the passageways 9, 9 in alignment with the passageways 8, 8 in the L-bar 4, and the bolts 10, 10 are inserted through the passageways and the nuts 11, 11 screwed onto the bolts to bring the back bar 6 tightly against the L-bar 4, with the upturned end of the back bar 6 bearing against the bottom surface of the L-bar 4. As the heat from points 2, 3 generates, it will be absorbed and conducted through the L-bar 4 and dissipated through the fins 7, 7, thus maintaining cooler points and transmitting a maximum electric current therethrough, and by maintaining the points at a cool temperature, reducing carbon formation thereon and increasing the life of the points, as well as the efficiency of the ignition system.

While the foregoing is a preferred embodiment of the invention, it is by way of illustration only, the broad principle of the invention being defined by the appended claim.

I claim:

1. In an ignition point heat absorber, a heat conductor mounted on the framework of an ignition point system having means for dissipating heat generated by said system, said conductor consisting of an L-bar having an orifice therein adapted to receive the fixed point of the ignition system, a back-bar having one end upturned to bear against said L-bar and adapted to anchor said L-bar on to the ignition system framework and means for maintaining said back-bar in releasable position on said ignition system.
